UNITED STATES PATENT OFFICE.

BERTIE EUGENE CASSELL, OF SPARLAND, ILLINOIS.

WINDMILL.

No. 882,871.

Specification of Letters Patent. Patented March 24, 1908.

Application filed October 5, 1906. Serial No. 337,609.

To all whom it may concern:

Be it known that I, BERTIE EUGENE CASSELL, a citizen of the United States, residing at Sparland, in the county of Marshall and State of Illinois, have invented a certain new and useful Improvement in Windmills, of which the following is a specification.

My invention relates to wind mills; and it has for one of its objects to provide a wind mill in which the driving connection for transmitting motion from the wind wheel to a pump or other device or devices to be actuated is entirely inclosed and protected from the weather with a view of prolonging the usefulness of the mill.

Another object of the invention is the provision of improved means for automatically braking or bringing to a gradual stop the wind wheel and driving connection of a wind mill when the wheel is thrown out of the wind.

Other advantageous features peculiar to my invention will be fully understood from the following description and claims when the same are considered in connection with the accompanying drawings, constituting part of this specification, in which:

Figure 1 is an elevation, partly in section, of my improved wind mill as the same appears when the wind mill is out of the wind. Fig. 2 is a detail top plan view illustrating the housing of the mill and the vane pivoted to said housing. Fig. 3 is a view, partly in elevation and partly in section, taken at a right angle to Fig. 2. Fig. 4 is a detail vertical section illustrating the lower portion of the driving connection. Fig. 5 is a detail elevation of the swivel joint intermediate the driving connection and the pump rod. Fig. 6 is a detail view, partly in elevation and partly in section, of the driving connection taken at a right angle to Fig. 4. Fig. 7 is an enlarged, detail perspective view of one section of the rotary support for the driving connection. Fig. 8 is an enlarged, detail elevation illustrating a modified construction as the same appears when the wheel is put in the wind. Fig. 9 is an enlarged elevation of the sheave of said modified construction, re- moved.

Referring by numeral to the said drawings and more particularly to Figs. 1 to 7, thereof: 1 is the frame of the mill which may be of the conventional or any other construction compatible with the purposes of my invention.

2 is a pump which is represented as an example of device to be actuated and is provided with the usual piston rod 3, and 4 is the before mentioned rotatable support for the driving connection, as a whole. The said 60 rotatable support 4 comprises a housing 5, supported and adapted to turn on its axis on the top of the frame 1 and having a removable door 6 to permit of access being readily gained to the parts which it incloses, and also 65 having a lateral sleeve 7 extending from a point opposite the door 6, a tube 8 communicating with the interior of and depending from the housing 5 and occupying the vertical center of the frame 1, a section 9 having 70 a split, tubular upper portion 10, fixed in the lower end of the tube, 8; and a section 11, bolted at 12, Fig. 6, to the section 9 and having an enlargement 13 bearing on a standard 14 rising from a cross bar 15 of frame 1 and 75 also having a depending tube 16 journaled in said standard 14 and cross bar 15.

17 is a shaft journaled in the sleeve 7 of the housing 5. At its outer end this shaft 17 has fixed on it a wind wheel 18, of the conventional construction or any other construction suitable to the manufacturer, while on its inner end is fixed a peripherally grooved pulley 19, Fig. 3, which is contained in the housing 5 and is arranged opposite the door 6, as shown 80 in Fig. 3.

20 is a peripherally grooved pulley, fixed on a shaft 21, journaled in the section 11 of the rotatable support 4.

22, 22 are anti-friction and guide sheaves 90 mounted in the lower portion of the housing 5.

23, 23 are anti-friction and guide sheaves mounted on the section 9 of rotary support 4, and 24 is a belt, of rope, chain or other material suitable to the purpose, mounted on and connecting the pulleys 19 and 20 and arranged in engagement with the sheaves 22 and 23 after the manner shown in Figs. 1, 4 and 6. In virtue of this construction it will be observed that when the wind wheel 18 is in the wind and the pulley 19 is rotated, the pulley 20 will be rotated; and it will also be observed that the sheaves 22 and 23 hold the stretches of the belt 24 out of contact with 100 the tube 8, and that the housing 5 and tube 8 inclose the pulley 19 and belt 24 and efficiently protect the same against the weather. It will further be observed that the support 4 as a whole is free to turn on its axis in the 110

frame 1, and hence will not interfere with the wheel 18 being put into and out of the wind, as will be presently described.

25 is a hood fixed to the frame 1 and loosely surrounding the tube 8 in a position slightly above the pulley 20 and sheaves 23. This hood has for its office to protect the said sheaves and pulley from rain, snow, etc.

26 is a pitman pivoted to the side of the pulley 20, off the center thereof, and provided at its lower end with an anti-friction wheel 27 which is movable up and down in the tube 16.

28 is a rod pivotally connected to and depending from the lower end of pitman 26, and 29 is a rod fixedly connected to the rod 28 and connected through a swivel joint 30 with the pump rod 3. From this construction it follows that when the wind wheel is in operation, the rotary motion of the pulley 20 will be converted into reciprocatory motion and utilized to actuate the pump rod 3. At this point I desire it understood that when deemed expedient or desirable rotary motion may be taken from the shaft 21 of pulley 20 to actuate machinery of various kinds.

30^a is a horizontally swinging vane, pivoted at 31 to the housing 5.

32 is a tractile spring interposed between the housing 5 and the vane 30^a, and having for its function to draw the vane to and normally hold the same in a position at a right angle to the wind wheel 18 and against a brace arm 33 fixed to the housing 5 so as to put and retain the wind wheel 18 in the wind.

34 is a cable connected to the vane 30^a and passed over a sheave 35^a which hangs on a swivel on the housing and down through the hollow, rotary support 4, and 36 is a windlass 40 to which the cable 34 is connected and on which it is designed to be wound; the said windlass being provided with a ratchet which is engaged by a pawl as shown to prevent casual retrograde rotation of the windlass.

45 It will be apparent that when the windlass 36 is turned in the direction to wind up the cable 34, the vane 30^a will be drawn to and retained in a position parallel to the wheel 18 and in consequence the wheel will be moved 50 and held out of the wind.

With a view of braking or gradually stopping the wheel 18 and the driving connection intermediate the same and the pump rod 3 when the wheel 18 is put out of the wind, I 55 provide the rod 37. This rod is mounted in the housing 5 and its inner end is arranged to bear against the face of the pulley 19 while its outer end is arranged to be engaged by a portion of the vane 30^a. Thus when the vane 60 30 is moved to a position to put the wheel 18 out of the wind, it will press the rod 37 inward, and by so doing will cause said rod to frictionally engage the pulley 19 so as to bring said pulley and the wind wheel and the 65 parts connected therewith to a gradual stop.

On the movement of the vane 30^a to a position at a right angle to the wheel 18, the rod 37 will obviously be relieved of pressure, and the pulley 19 will be left free to turn.

In the modified construction shown in 70 Figs. 8 and 9, the vane 30^a is, through the medium of a tractile spring 32^a, drawn to and held in a position parallel to the wheel 18 and so as to press the rod 37 against the pulley 19 for the purpose before described, while the 75 vane is moved to and retained in a position at a right angle to the wheel 18 and against the brace arm 33^a through the medium of a cable 34^a which is connected to the vane and the windlass 36 and is passed over a sheave 35^a, Figs. 8 and 9, and through an aperture in the hollow rotary support 4 and is contained in said support 4.

It is obvious that in practice pulleys and a belt other than those shown and described 85 and suitable to the purposes of my invention may be employed in the discretion of the manufacturer without involving departure from the scope of my invention as claimed. I also desire it understood that when deemed 90 necessary a suitable fender 40 may be employed for holding the cable or chain 34 attached to the windlass 36 against becoming entangled in the lower pulley 20.

It will be gathered from the foregoing that 95 both embodiments of my invention are simple and compact in construction and at the same time are well adapted to withstand the usage to which wind mills are ordinarily subjected.

The constructions shown and described 100 constitute the preferred embodiments of my invention, but I desire it understood that in practice such changes in the form, construction and relative arrangement of parts may 105 be made as fairly fall within the scope of my claimed invention.

Having described my invention, what I 110 claim and desire to secure by Letters Patent, is:

1. A windmill comprising a frame; a hollow rotatable support mounted in said frame and carrying a housing at its upper end; a windwheel journaled in said housing; a pulley in said housing adapted to be rotated by 115 said windwheel; a vane projecting from the opposite side of said housing; a split tubular section carried by the lower end of said rotatable support and terminating in a flat open section; a tubular section mounted in the 120 lower portion of said frame and having a projecting flat open portion that is connected with the open section of the split tubular portion; a pulley mounted in the flat open projecting portion of said lower tube, and a cable connecting the said two pulleys.

2. The combination in a windmill, of a frame, an upright, rotary and hollow support journaled in said frame and having a housing at its upper end, disposed above the 130

frame, a lower pulley mounted on the lower portion of the hollow, rotary support, a shaft journaled in the housing and bearing a wind-wheel; an upper pulley fixed on said shaft and contained in the housing, lower and upper pairs of anti-friction and guide sheaves carried by the hollow, rotary support, a connecting belt mounted on the pulleys and engaged with said sheaves and extending through the housing and having its stretches disposed in the hollow, rotary support, a tube

fixed to and depending from a hollow, rotary support, a pitman pivoted to the lower pulley off the center thereof and having an anti-friction wheel movable up and down in said tube, 15 a rod pivotally connected to and depending from the pitman, and a second rod swiveled to the said rod.

BERTIE EUGENE CASSELL.
